(57) **CLAIM**

The ornamental design for a handle for surgical instrument, as shown and described.

DESCRIPTION

FIG. 1 is a front elevational view of the handle for surgical instrument;

FIG. 2 is a rear elevational view thereof;

FIG. 3 is a left side elevational view thereof;

FIG. 4 is a right side elevation view thereof;

FIG. 5 is a top plan view thereof;

FIG. 6 is a bottom plan view thereof;

FIG. 7 is a front perspective view thereof; and,

FIG. 8 is a rear perspective view thereof.

The broken line areas show portions of the handle for surgical instrument that form no part of the claimed design.

1 Claim, 8 Drawing Sheets
